UNITED STATES PATENT OFFICE.

MERTON D. PHELAN, OF LYNN, MASSACHUSETTS, ASSIGNOR, BY MESNE ASSIGNMENTS, TO
THOMAS G. PLANT, OF BOSTON, MASSACHUSETTS.

STAPLE-TACKER.

No. 883,824.

Specification of Letters Patent.

Patented April 7, 1908.

Application filed July 16, 1906. Serial No. 326,370.

To all whom it may concern:

Be it known that I, MERTON D. PHELAN, a citizen of the United States, residing at Lynn, in the county of Essex, State of Massachusetts, have invented an Improvement in Staple-Tackers, of which the following description, in connection with the accompanying drawings, is a specification, like letters on the drawings representing like parts.

10 My invention relates to metallic fastening machines, more particularly to such as form and drive staples from a continuous strip of metal or wire.

Machines of this type in common use are 15 usually provided with staple forming and driving mechanism, cutting mechanism and feeding mechanism, the latter operating to feed the end of a continuous strip of metal or wire toward the cutting and staple forming 20 and driving mechanisms, the cutter mechanism operating to cut desired lengths from the infed end of wire and center them over the anvil of the forming mechanism upon which they are bent and shaped into required form 25 and then driven into the work.

If the feeding mechanism fails uniformly 30 to feed the desired wire lengths, it is clear that the fasteners made therefrom will lack uniformity, and as heretofore generally constructed the feeding mechanism for machines 35 of this type have been provided with pawl and ratchet wheel feeds which through the outgrowth of many years of development have nevertheless failed to furnish reliable and uniform results.

My invention aims to provide a novel feeding mechanism of simple construction and operation that secures a uniform and positive feed of the strip from which the fasteners 40 are to be made.

My invention also contemplates novel adjusting means for varying the position of the forming mechanism relative to the cutting mechanism and for correspondingly adjusting the feeding movement thereby to the 45 length of the staples.

The above, with other features and objects 50 of my invention will be best understood and appreciated from a description of one embodiment thereof, selected for purposes of illustration and shown in the accompanying drawings, the scope of the invention being more particularly pointed out in the appended claims.

55 Referring to the drawings,—Figure 1 is a

front elevation of a preferred embodiment of my invention in a staple forming and driving machine selected for illustration, the base or lower part of the column being removed; Fig. 2 is a transverse vertical section taken 60 through the stud that supports the movable head or carrier in which the staple forming and driving mechanism is mounted; and, Fig. 3, a transverse, horizontal section taken on the line 3—3, Fig. 2.

65 The fastener or staple forming and driving mechanism generally may be of any suitable or desired construction, hence in the following description I shall merely refer in outline to the principal parts of such a mechanism 70 selected for illustration herein and shown in the drawings but will not enter into any minute description thereof.

The column 1, is of suitable shape and construction to support the working parts and is 75 provided at its upper end with a head or frame, 2, on which is a movable carrier, 3, for the staple driving and forming mechanism. This head at the opposite side thereof, is also provided with a horizontal bracket, 4, which 80 supports the sliding feeding block, 5, a stationary lower cutter, 6, and its coöperating vertically movable upper cutter, 7, said cutters being positioned between said feed block and the carrier 3. Said head frame, 2, 85 is further provided with suitable bearings for a horizontal drive shaft, 8, adapted to be rotated when desired by a suitable drive pulley, 9, mounted on its rear end, and to operate the several mechanisms referred to. 90 The movable carrier or head, 3, referred to at the right side of the frame, in the present instance, is slidably mounted on horizontal studs, 10, tapped into said frame. This arrangement permits the staple forming and 95 driving mechanism thereon to be moved towards the cutting and feeding mechanisms, referred to, and mounted on the frame so that staples may be formed of different lengths as is customary in machines of this type. At 100 its front this carrier or head, 3, is provided (see Fig. 3) with a vertical groove or guide way, 11, in which the staple forming and driving mechanisms proper are carried and which comprise the vertically reciprocating 105 staple former, 12, (Fig. 3), slidably mounted in said guide way, 11, and provided at its rear face with a staple forming groove, 13 (Fig. 1), the horizontal in and out reciprocable anvil member, 14 (Fig. 2), having at its 110

front end the anvil proper, 15 (Fig. 1), over which the staple blanks are bent or shaped; and the driver bar, 16 (Figs. 1 and 3), the lower end of which is provided with a suitable driver, (not shown) adapted to drive staples through the throat, 17, of the machine into the work held up against it.

For vertically reciprocating the staple former, 12, to cause it to bend or shape the staple blank over the anvil, 15, below it, any suitable means may be employed, that herein shown comprising a bell crank, 18 (see Figs. 1 and 3), fulcrumed at 19 to said frame, 2, the front forked end of which engages a stud, 21 (Figs. 1 and 3), projecting horizontally from the right side of said former, the rear vertical arm of said bell crank carrying usual roller or other stud, 22 (see dotted lines Fig. 2), which is actuated by a cam, 23, on said drive shaft. Rotation of the drive shaft and said cam oscillates said bell crank and alternately depresses and elevates the staple former connected therewith. The forked end of the lever, 18, by its engagement with the stud, 21, also permits adjustment of the carrier or head, 3, toward or from the cutting and feeding mechanisms referred to without interfering with the operation of said staple former. For reciprocating the anvil member, 14, to project its anvil, 15, forward beneath the staple former, 12, and to withdraw it to permit the staple to be driven down past it by the staple driver, the rear end of said anvil member, in the present instance, is connected with another bell crank, 24 (Fig. 3), fulcrumed at 25 to said frame, its rear vertical arm carrying the usual roller (not shown) operated by a shaft cam (not shown) in the usual manner.

The driver bar, 16 (Figs. 1 and 3) is mounted to slide in a vertical groove or guide way, 26, formed in the back of said former, 12, the latter as stated mounted in the guide way, 11, referred to, and retained therein by a suitable face plate, 27 (Figs. 1 and 3), secured to the front face of said carrier. At its upper end said driver bar 16, is slidably connected by means of a horizontal dove-tailed projection, 28, with a transverse groove of converse shape in the lower end of an actuator bar, 29, slidably mounted for vertical reciprocation in a fixed guide way, 30, at the upper front portion of the frame head, 2. This arrangement permits the carrier and its driver bar to be moved or adjusted laterally with and to follow adjustment of the former without losing its driving engagement with the driver actuator. This actuator, 29, (see Fig. 1), is actuated by a strut, 31, in turn actuated by the spring pressed arm, 32, pivoted on the end of a horizontal rod, 33, and oscillated in an upwardly projecting arm of said frame or head, 2. The coil spring, 34, surrounding said rod, 33, and which furnishes the power to actuate said arm, is provided with suitable

adjusting means for varying its tension, whereby the actuator and driver may be operated to drive the latter with desired force. This adjusting means comprises a handle operated ratchet wheel, 35 (Fig. 1), to which the fixed end of said spring is attached and a spring actuated pawl, 36, rotation of the ratchet by its handle causing said pawl, 36, to engage one or another of its teeth and move the normally fixed end of said spring to tension the same, and thereby vary the force exerted by its opposite end upon said arm. The arm, 32, is raised and held elevated against the tension of said spring by a cam, 37, on the front end of the drive shaft, 80 8, the foot of said actuating bar extending rearwardly into the path of said cam to be lifted thereby and retained in elevated position until the high part of the cam rotates or passes from under it when the driver is sharply driven down by the action of said spring.

To provide suitable means for adjusting the staple forming and driving mechanism toward and from the strip feeding and cutting mechanisms, their carrier head, 3, is provided at its rear with an upwardly extended ear, 40 (Fig. 2), in which is rotatably or adjustably mounted a stud or bushing, 41, carrying eccentrically a stud or pin, 42, on the end of an arm, 43. This arm is pivotally connected by a link, 44, (Figs. 2 and 3), with a depending arm, 45, of a horizontal adjusting lever, 46, fulcrumed upon a stud 47 (Figs. 1 and 3), mounted in a laterally extended arm, 87, of said frame, 2. By swinging this lever vertically the link, 44, connected to its depending arm and to the said head, 3, is swung in and out, moving said head with it, so that the latter may be moved to any desired position relative to the cutting and feeding mechanisms to position the anvil, 15, at such point under and between the ends of the straight wire blank fed thereon as will cause the ends of said blank when folded or formed down over said anvil to produce a staple, the legs of which are of desired relative length. To facilitate turning the stud or bushing, 41, in its bearings for the purpose of adjusting the position of the carrier relative to its lever, 46, its outer front end is provided with a hexagonal head to which a wrench or key may be applied for adjusting purposes. The front end of said eccentric pin, 42, is threaded to receive a clamping nut, 48 (Fig. 3), by which the said arm may be clamped in any desired position after angular adjustment relative to said lever, 46, or the bushing, 41, which also provides for adjusting the carrier, as described, independently of that effected by the adjustment of said bushing. The operation of this part of the mechanism, however, and also that produced by the adjustment of said lever, 46, will be best understood after 130

the description of the feeding and cutting mechanism has been given.

The movable cutter, 7, of the cutting mechanism is adjustably secured to a block, 54, on a vertically reciprocable slide, 55, mounted in suitable guide ways, 56, on the frame bracket, 4, and is reciprocated vertically, relative to the stationary cutter, 6, by a bell crank, 57, fulcrumed on said stud, 19 (Fig. 3), which is extended horizontally to the left side of said frame, 2, for this purpose. The vertical arm of this bell crank is provided with a roller or other stud actuated by a cam (not shown) on said shaft, 8. This 15 cam is a face cam and its lever is held against it by a coil spring, 60 (Figs. 1 and 2), connecting its horizontal arm with a point on said frame adjacent the front bearings of the drive shaft.

20 To provide for pointing the ends of the staple legs, the cutting edges of the cutters are positioned at an angle to the path of the staple strip or wire, so that a diagonal cut is produced across the ends of the strip. The 25 cutters are adjustably mounted and held in desired position by bolts, 61, and may be adjusted to compensate for wear or to meet the requirements of the work, for instance in using strips or wire of different dimensions.

30 I will next describe the novel feeding mechanism, which I have provided to coöperate with the foregoing or any other staple forming and driving mechanism and in which the variations in feed movement is produced 35 by the adjustment of said adjusting hand lever, 46. In the present embodiment of my invention (see Fig. 2) this feeding mechanism comprises the feed block, 5, referred to, which is slidably mounted in horizontal 40 guide ways, 62, on said bracket, 4, and a feed pawl, 63, best shown in Fig. 2, fast on a horizontal pin or shaft, 64, mounted in vertical ears of said block, 5. This block is normally retained in outer position by a coil 45 spring, 66, connecting said feed block with a vertical pin on said bracket and acting to draw the block towards it. The block is also provided with suitable end guides, 67, beneath which the wire or metal strip to be fed 50 is placed, and which is thereby guided upon the upper face of said block, toward which the pawl is swung to grip the wire firmly against the block and move the same toward 55 said cutters, 6 and 7. To operate this feeding device, as herein, the pawl carrying pin, 64, is provided at its rear end with a depending arm, 68 (Fig. 2), connected by a link, 69, with the lower end of a vertical actuating lever, 70, fulcrumed at 71 on a lug or arm, 71^a, of said frame 2. At its upper end this actuating lever is connected by a link, 72, with a slide or block, 73, the sides of which embrace 60 a curved tail piece or arm, 74, of a cam yoke or lever, 75 (Fig. 2), pivoted on a horizontal

stud, 75^a, tapped into the front of said frame, 2. The arms of this yoke embrace a cam, 76, of approximate triangular shape, eccentrically mounted on the front end of said drive shaft, 8, rotation of which oscillates said lever, and through the intermediate connections causes said gripping pawl, 63, to swing inwardly to grip the wire resting on said feed block and press it firmly against said block and by its further movement slide said block and the clamped wire inwardly together to feed the wire the desired distance to bring the center of the subsequently severed blank upon the anvil 15. On a return movement of the feed block the feed pawl swings outwardly free from the wire and permits the said block to slide along the wire into position for a new grip preparatory to a succeeding feed. As here shown, the yoke arms are provided with the usual wear plates adjustably mounted thereon, so that they 85 may be adjusted to compensate for wear. That said feed block, 5, may be positively returned outwardly to its normal position without placing reliance therefor upon the retracting spring, 66, the lower arm of the 90 oscillatory actuator lever is provided with a depending finger, 77 (Figs. 2 and 3) adapted to engage with a spring pressed pin, 78 (see Figs. 2 and 3), socketed at the rear side of the feed block and normally supported by a coil 95 spring, 79, seated behind it and against an adjustable screw plug, 79^a, threaded into the bottom or outer end of said socket. In the operation of the machine, the outward swing of the lower arm of said actuating lever, to the left (Fig. 2), causes said finger, 77, to strike said spring pressed pin, pushing it to the left, compressing its spring and thereby positively sliding the block before it in case the retracting spring, 66, has not already returned said block. The finger may or may not be caused to engage the slide block itself as it pushes the pin home before it, that being regulated by the adjustment of said spring, 79, by its screw plug. By this 100 arrangement the movements of the feed block are positive in both directions and to prevent vibrations and loose action of the connected parts, the bottom of the guide way, 62, is provided with a spring pressed 105 friction washer, 80 (Fig. 2) held elevated by a coil spring, 81, seated below it upon a vertically adjustable screw plug, 82.

Between the feed pawl and the cutter I have arranged a spring pressed over-hanging back stop pawl, 50 (Figs. 1 and 3) which is pivoted on a lug, 51, of said bracket, 4, and operates to prevent retraction of the wire during the outward or return slide of the feeding block but permits in-feeding of said 120 wire or strip. This lug, 51, is also provided with a spring, 52, the tension of which may be varied by means of the adjusting screw,

53, mounted therein by which the pressure of said pawl, 50, against the wire may be varied as desired.

Referring now to Fig. 2, it will be noted that the active face of the cam, 76, is concentric with the drive shaft, 8, and is provided with a dwell, 83, of such length that it is in approximately constant engagement with either one of the other of said yoke arms, so that movements of the adjusting lever, 46, do not move the cam yoke or lever, 75, or the normal position of the feeding block, 5, and its wire gripping pawl, 65. The curve of the tail piece or depending arm of the yoke, 75, has its center of curvature at the pivot connection of the link, 72, with the actuator lever, 70, so that adjustment of the slide or block, 73, on said tail piece does not operate to move said actuator lever, 70, or the feed block, 5, connected therewith, but changes merely the effective radial length of said tail piece and thereby the length of movement imparted to the feed block by a fixed oscillation of said yoke. This slide block, 73 (see Fig. 3), is provided with an inwardly projecting removable member, 84, received in a longitudinal groove, 85, in the outer curved face of said tail piece or arm, 74, so as to prevent displacement of said block and to permit of its removal upon removing said member, 84. For elevating or depressing the adjustable slide block on said tail piece to vary the effective length of the latter as stated, said block is connected by a link, 86, with the inner end of said horizontal adjusting lever, 46, elevation or depression of said end moving said link and the block connected therewith toward or from the yoke as desired. It will now be apparent that by the movement of this lever both the position of the staple forming and driving mechanism may be moved toward and from the cutting mechanism and the feed movement may be adjusted to correspond, so that the anvil, 15, is centered or positioned intermediate the infed end of said strip or wire and the stationary cutter, 6.

As the slide block, 73, in the yoke lever, 75, is moved toward and from the fulcrum by the depression or elevation of the adjusting lever, 46, the arc of oscillation of said block and the feeding movement of the wire are diminished or increased accordingly, so that the feeding movement of the wire or metal strip employed is always substantially twice the length of the staple desired, the distance between the anvil and cutters being substantially half such length. If, for example, the anvil is moved $1/16''$ toward or from the cutter, it is obvious that the feeding movement should be respectively decreased or increased by $1/8''$ and the arrangement is such as to always produce such proportionate adjustment, so that the anvil will always be in the center of the severed blank

when adjusted to cut staples having equal legs irrespective of the length or size of the staple.

By adjusting the bushing, 41, in its bearing or by turning the eccentric pin arm, 43, therein, any desired inequality in the length of the staples may be secured since this adjustment does not move the slide block, 73. Furthermore, this arrangement permits maintaining any desired inequality in the lengths of staple legs with all sizes of staples or to vary it, as desired. When it is desired to use staples having legs of unequal lengths, the nut, 48, may be unscrewed slightly, sufficient to permit turning the arm, 43, and its pin, 42, in said bushing, 41, which, since the depending arm of the lever remains stationary, will throw the movable carrier, 31, inward or outward as may be desired. Furthermore the bushing or stud, 41, may also be turned in its bearing to vary the position of said pin, 42, relative to the head, 3, these two adjustments permitting almost any desired variation in the lengths of the staple legs, and which as is readily apparent, are independent of the adjusting lever, and also of the cutting and feeding mechanism. The movement of the staple former is timed to take place simultaneously or immediately following that of the movable cutter to cause it to engage the length severed by the cutting mechanism and shape it over the anvil, after which the anvil is withdrawn and the driver bar sprung down to insert or drive the staple thus formed.

That the adjusting lever may be held in a predetermined position to produce staples of desired lengths, the horizontal frame arm, 87, upon which the lever is fulcrumed, is provided with a segmental portion, 88 (Fig. 2), which supports a pair of arc shaped vertical guides, 89 (Figs. 2 and 3), between which the outer arm of said lever moves. The outer curved sides of these guides are provided with V-shaped notches, 90, corresponding to the length of staples desired and to the corresponding amount of feed required, and opposite which said lever must be moved to produce staples of that length.

For holding the adjusting lever in the desired position its outer end is provided with a transverse slot in which is slidably mounted a latch member, 91 (Fig. 3) extending through and slidably mounted in said slots, with its inner end in engagement with said notches. The outer end of this adjusting lever, 46, is formed as a tubular handle, 93, within the bore of which is a coil spring, 94, interposed between an adjustable plug or screw, 95, threaded into its outer end and said latch member, 91, and operating to thrust the latch into engagement with the notches of said rack.

The inner face of the latch is wedge shaped or provided with inclined faces to fit into

100

90

130

said V - shaped notches, 90, whereby, upon the application of sufficient power to the handle end of the lever, the wedge action produced between the pawl and said notches 5 forces the latch outwardly against the tension of said spring, 99, so that the lever can be moved from notch to notch as desired, the latch entering into and being forced out of each notch in turn. Obviously the adjustment 10 of the screw plug, 95, permits adjustment of the tension of said spring, 94, to vary the force required to move said handle and its lever.

That the adjusting lever may be stopped opposite any desired notch to produce the 15 required length of staples and also to adjust the feed mechanism correspondingly, a pair of adjustable stop screws, 96, are provided which are mounted in suitable horizontal arms, 97, secured to said segmental portion, 20 88, one of these stops being positioned above, the other below said lever, each of which may be moved in and out to limit the vertical movements of the lever. By this arrangement the adjusting lever may be rapidly 25 moved from one position to another, which is of ~~especial~~ value when but two lengths of staples are employed since it saves considerable time. The strip of metal or wire, 98, from which the staples are formed may be 30 carried in any convenient manner, for example, upon a reel, 99, mounted upon a suitable arm, 100, secured to said frame, 2.

In practice, the machine operates as follows: The strip of metal or wire being brought 35 down from the reel is inserted through the guides in the feed block 5, and under the feed pawl, 50, of the inner guide way and to and over the anvil. The drive shaft being then rotated, the oscillations of the cam yoke 40 through its connections with the wire gripping pawl, 63, causes it to clamp the wire against the feed block, 5, and slide it inward for feeding after which it is retracted by its spring or by the action of the said finger, 77, 45 as described. Immediately following the in-feeding movement of the wire the movable cutter is depressed to sever a length from the end of said wire or strip and to point its end in the manner described, immediately 50 following which the staple former descends and bends the severed length over the anvil, 15, while the groove in its back shapes it into desired staple form. Simultaneously with these movements the cam, 37, on the drive 55 shaft engages and lifts the foot of the actuator member and holds it in elevated position until subsequently rotated from beneath it during which time the anvil, 15, is withdrawn by the action of its bell crank and 60 the cam controlling its movements. Simultaneously or immediately following the withdrawal of the anvil, the cam, 37, releases the foot of the driver bar and permits it to be driven sharply down by the operating spring, 65 and cause its driver to engage the staple as

it is released by the anvil and drive it through the throat, 17, into the work held up against the same. To adjust the length of staples to another length the adjusting lever is forcibly elevated or depressed to bring its 70 latch number into engagement with a notch corresponding to the length of staple required and also to vary the feed of the wire proportionately to produce such staple, the screw stops being adjusted when desired to 75 cause the latch to engage any of said notches, so that it is not necessary to determine which notch is the one desired.

My invention provides a machine that is certain in action or operation, the feeding 80 mechanism always producing a uniform feed for the desired adjustment and one that does not vary with different speeds of operation, thereby avoiding the objectionable and unreliable ratchet pawl and shield or equivalent 85 mechanisms hitherto commonly employed in machines of this type, the present feeding mechanism being extremely simple in construction and operation. The adjusting mechanism for the feed is also positive and 90 produces a uniform result. The novel and positive feeding mechanism, its adjusting mechanism, with that for adjusting independently the carrier to provide for inequalities in the lengths of staple legs, are each and 95 all, so far as I am aware, original with me.

While in the particular embodiment of my invention as herein described, the novel feeding mechanism has been shown in connection with staple forming and driving 100 mechanism, obviously my invention is not limited thereto, being equally suitable for use with any machine in which a continuous wire or strip of metal is fed to fastener forming or driving mechanisms.

I do not desire to claim herein the broad 105 subject matter expressed in the claims of the application of Perley R. Glass, Patent No. 871,991, dated November 26, 1907, as the same is not of my invention.

The construction and operation of a single 110 illustrative embodiment of my invention having been fully described, and it being obvious that the invention is not limited to the particular form and arrangement of the several parts, but may be variously modified 115 without departing from its spirit or scope,

I claim and desire to secure by Letters Patent:—

1. In a metallic fastener machine, the combination of a movable carrier 3, staple forming and driving means carried thereby, a wire feeding block 5, a lever 70 for reciprocating said block, a yoke 75 having a tail piece 74, a block 73 slidably mounted on said tail 120 piece and operatively joined to said lever 70, an adjusting lever 46, and connections between the adjusting lever 46, the carrier 3, and block 73 for simultaneously adjusting 125 said carrier and block. 130

2. In a machine of the type described, the combination of cutting mechanism, a head or carrier provided with staple forming mechanism and movable toward and from said cutting mechanism, with a lever and connections for adjusting said head or carrier, comprising a stud or bushing mounted in said head, a pin eccentrically mounted therein and provided with an arm, and means for connecting said arm with said lever whereby elevation or depression of the latter moves said carrier respectively from or toward said cutting mechanism.

3. In a machine of the type described, the combination of cutting mechanism, a head adjustable toward and from said cutting mechanism having an adjusting lever and connections for moving the same, said connections comprising the bushing, 41; the lever 43, having a pin 43, eccentrically and pivotally mounted on said bushing, 41, said bushing being rotatably mounted in said head and adapted to be turned to vary the position of said pin relative to said head to adjust the latter independently of said adjusting lever.

4. In a machine of the type described, cutting mechanism, a carrier or head provided with staple forming mechanism adjustable toward and from said cutting mechanism, a lever and connections for adjusting the same, said connections comprising a crank arm pivotally mounted in said head, with means for connecting it with said lever and for clamping it in adjusted position, whereby the adjustment of said head may be effected independently of the adjustment of said lever.

5. In a machine of the type described, the combination of wire feeding means, cutting means, staple forming means, and lever means for simultaneously adjusting said staple forming means and varying the feed of said feeding means to produce staples of different lengths, and eccentric means for variably positioning said staple forming means to vary the length of the staple legs.

6. In a machine of the type described, cut-

ting mechanism, fastening means, feeding mechanism, means for adjusting the position of said fastening means relatively to said cutting mechanism, and correspondingly to vary the feed of said feeding mechanism for producing fastenings of desired length, and eccentric means to adjust said forming means relatively to said adjusting means.

7. In a machine of the type described, cutting mechanism, staple forming means, means for adjusting the latter toward and from said cutting mechanism for varying the length of staples and eccentric means to adjust said staple forming means relatively to its adjusting means to produce staples having legs of unequal length.

8. In a machine of the type described, the combination of reciprocatory feeding means and wire severing mechanism, an actuator for said feeding means comprising a yoke having a tail piece and a block slidably mounted on said tail piece with fastening forming means an actuator therefor, connections intermediate the actuator and fastener forming means constructed and arranged to permit lateral movement of the fastener forming means, and a lever for adjusting the fastening forming means towards the position of said severing mechanism and correspondingly to vary the relation of the yoke and sliding block of the reciprocatory feeding means for varying a dimension of said fastening.

9. In a machine of the type described a carrier provided with fastening forming mechanism, cutting mechanism, means for adjusting the position of said carrier relative to said cutting mechanism, and means connected with said carrier for varying the adjustment produced by said adjusting means.

In testimony whereof, I have signed my name to this specification, in the presence of two subscribing witnesses.

MERTON D. PHELAN.
